UNITED STATES PATENT OFFICE.

SAMUEL S. BLOOM, OF NEW YORK, N. Y.

DESIGN FOR A CAMPAIGN BUTTON OR THE LIKE.

Application filed August 7, 1928 Serial No. 27,735. Term of patent 3½ years.

To all whom it may concern:

Be it known that I, SAMUEL S. BLOOM, a citizen of the United States, residing at New York, in the county of New York and State of New York, have invented a new, original, and ornamental Design for Campaign Button or the like, of which the following is a specification, reference being had to the accompanying drawing, forming a part thereof.

I claim:

The ornamental design for a campaign button or the like as shown.

SAMUEL S. BLOOM.
